UNITED STATES PATENT OFFICE.

HARRY TOPLITZKY, OF LOS ANGELES, CALIFORNIA.

DISINFECTANT-DISTRIBUTER.

1,207,346.

Specification of Letters Patent.

Patented Dec. 5, 1916.

Application filed December 8, 1915. Serial No. 65,806.

To all whom it may concern:

Be it known that I, HARRY TOPLITZKY, a citizen of the United States, residing at Los Angeles, in the county of Los Angeles 5 and State of California, have invented a new and useful Disinfectant-Distributer, of which the following is a specification.

This invention relates to improvements in liquid deodorizer disinfectant distributors of 10 the type in which the disinfectant is distributed in the form of an odorabile vapor as well as in liquid form.

The primary object of this invention is to provide a distributer of the character described which will thoroughly and effectively distribute the disinfectant in the form of an odorabile vapor so that objectionable odors may be overcome. In distributers now in general use the odorabile vapor is not 20 emanated quickly and thoroughly enough to overcome other objectionable odors because air is not permitted to circulate in sufficient quantities about the liquid to cause thorough distribution of the odorabile vapor and the 25 liquid is usually not sufficiently agitated to be subject to a quick evaporation. I provide means which will agitate and treat the liquid disinfectant so that it is subject to a thorough and quick evaporation to cause an 30 odorabile vapor to be thoroughly and quickly distributed.

Another object of this invention is to generally improve and simplify the construction and operation of distributers of the 35 character described so as to render them more effective, reliable and efficient in operation and inexpensive to manufacture.

Other objects and advantages will appear from the subjoined detail description.

40 The accompanying drawings illustrate the invention.

Figure 1 is a side elevation of the distributer partly in section; Fig. 2 is a vertical sectional view taken through the distributer; Fig. 3 is a horizontal sectional view taken on line 3—3 of Fig. 1; and Fig. 4 is a horizontal sectional view taken on line 4—4 of Fig. 1.

Referring to the drawings, 1 designates a 50 preferably cylindrical shell or casing which is open at both ends. A flanged lid 2 is hinged at 3 to the upper open end of the casing 1 and there is provided a spring catch 4 for locking the lid 2 in closed position.

55 The catch 4 comprises a strip of spring material 5 that is secured as at 6 at one end

interiorly of the casing 1 and extends above the casing into the lid 2. On its upper end the strip 5 is provided with a pin 7 which extends into an opening 8 formed in the side 60 wall of the lid 2. Located above the opening 8 is a larger opening 9 which provides for the insertion of a suitable tool for forcing the strip 5 inwardly and the pin 7 out of locking position in the opening 8. 65

Mounted on supporting lugs 10 within and spaced circumferentially from the casing 1 is a container 11 for liquid disinfectants and deodorizers. This container 11 is closed at its ends and the upper end thereof 70 terminates below the upper end of the casing a slight distance, whereas the lower end terminates at a point considerably spaced from the lower end of the casing. There is provided a filling opening 12 in the upper 75 end of the container 11 and a screw cap 13 closes said opening. Extending vertically and centrally through the container 11 is a wick tube 14 in which is mounted a wick 15. The wick 15 extends upwardly out of the 80 tube and back into the container 11 through an opening 16 located to one side of the tubing 14, so that the liquid in the container will be drawn by capillary attraction into that portion of the wick incased by the tube 85 14. The lower end of the tube 14 is open and the wick extends below said lower end so that the disinfectant or deodorizer will drip from the lower end of the wick and be distributed as will be later more fully described. 90

A bottom cap 17 formed similarly to the flanged lid 2 is provided centrally with a large air intake opening 18 and is detachably secured to the lower end of the casing 95 1 by means of bayonet connections 19.

Mounted within and resting upon the bottom of the cap 17 is an annular deflector and spreader member 20 of hollow substantially conical construction which receives the fluid 100 dropped from the wick 15 and has an irregular angular outer surface over which the liquid spreads. This member 20 is spaced circumferentially from the sides of the casing and cap 17 and is formed centrally upon its upper side with a conical projection 21 upon which the fluid drops. At the base of the conical projection the member 20 is formed with an annular lateral portion 22 and from the periphery 110 of the portion 22 the member 20 extends downwardly vertically as at 23 and termi-

nates in an annular lateral portion 24 similar to the one 22 and in a depending flange 25 which rests on the bottom of the member 17. A plurality of openings 26 are formed in the vertical portion 23 of the member 20. About the edge of the opening 18 is formed an upwardly extending annular flange or boss 27, mounted in which, is a tubular nozzle 28 which extends into the hollow member 20.

10 There is provided a drain tube 29 communicating with the bottom member 17 to distribute the disinfectant or deodorizer to the desired place. In this connection it will be noted that the flange 25 at the bottom of the member 20 is scalloped or cut away as at 15 30 to allow the fluid to flow into the tube 29. The bottom of the member 17 is inclined so as to cause the fluid to flow toward the center thereof and the flange 27 prevents the fluid from overflowing through the opening 18. A plurality of openings or perforations 20 31 are formed in the casing 1 between the lower end of the container 11 and the deflector 20. These openings allow for the escape of the evaporated liquid or the odor 25 36 of the disinfectant or deodorizer and permit a circulation of air through the opening 18, openings 26 in the portion 23 of the member 30 41 20 and casing 1.

35 In operation, assuming the container 11 to be filled with a liquid deodorizer or disinfectant the wick 15 will by capillary attraction cause the liquid to drop from the lower 40 45 end thereof upon the point of the conical portion 21 of the deflector and spreader 20. The liquid dropping upon the point of the conical portion 21 will be broken up, agitated and spread out in a thin film over the sides 40 45 thereof and flow slowly over the portion 22 of the member 20 and down the outer side of the portion 23 over the openings 26. Air is continually passing upwardly through the opening 18 into the member 20 and out of 50 55 the member 20 through the openings 26. A large amount of the liquid flowing over the openings 26 is therefore evaporated and this gives a light odoriferous vapor which passes upwardly into the casing 1 and out through the openings 31. This same effect will be had as the liquid flows over the openings or scalloped portion 30 and the liquid upon reaching the inclined bottom of the cap 17 will find its way to the discharge tube 29 and be distributed to the point determined upon. The nozzle 28 directs the air passing up through the opening 18 upwardly into the member 20 so that it will pass out through the openings 26. 60 Access to the container 11 may be readily had by releasing the catch 4 and swinging the lid 2 open on its hinge 3.

65 I consider the deflector and spreader member 20, also the peculiarly constructed cap 17 to be the most essential features of my inven-

tion. The liquid dropping from the wick 15 upon the member 20 is caused to spread out over the irregular surface of the member 20 in a thin film, covers a comparatively large area and is agitated so that an effective and rapid evaporation of a sufficiently large amount of the liquid takes place and a strong odoriferous vapor is quickly given forth from the device. The opening in the cap 17 in combination with the hollow spreader and deflector 20 provides for a constant draft or up-rush of air which in passing out through the openings 26 encounters the thin film of disinfectant or deodorizer and causes it to break up quickly or be 70 75 80 evaporated and distributed.

It is understood that the invention is not limited to the exact construction shown in the drawings and described above, but that deviations therefrom may be made within 85 the spirit and scope of the invention.

I claim:

1. A distributor for disinfectants and deodorizers comprising a casing, a container for liquid disinfectants and deodorizers mounted within the casing, a deflector and spreader member mounted in the casing below the container and being of hollow construction, said member having openings in the sides thereof, means to feed the liquid from the container onto the deflector, said casing having openings in the sides thereof above the deflector and provided with an air entrance opening at the lower end thereof below and communicating 90 95 with the interior of the deflector member. 100

2. A distributor of the character described comprising a casing, a container for a liquid disinfectant or deodorizer mounted in the casing, a deflecting and spreading member mounted within the casing below the container, means to feed the liquid onto the deflector and spreader, said deflector and spreader being of substantially conical outline and hollow, said casing having outlet openings therein above the deflector, said deflector having openings therein, and a liquid outlet in the bottom of said casing, said casing having a relatively large air inlet in the bottom thereof communicating 110 115 with the interior of the deflector.

3. A distributor of the character described comprising a shell, a container for a disinfectant or deodorizer mounted within the shell, a cap removably mounted upon and closing the lower end of said shell, said cap having a relatively large air inlet opening therein, a hollow substantially conical deflector and spreader mounted within the casing upon said cap, said spreader having openings in its sides communicating with the opening in the cap, said casing having openings therein above the spreader, and means to feed the liquid from the container onto the deflector. 120 125 130

4. A distributor of the character described comprising a casing being open at both ends, a lid hinged to and adapted to close the upper end of the casing, a container for a liquid disinfectant or deodorizer mounted within the casing, a cap closing the lower end of said casing, and having an air inlet opening centrally thereof, a liquid outlet tube communicating with said casing extending through the cap, a substantially conical deflector and spreader mounted within the casing and supported by the cap, said spreader having openings therein communicating with the opening in the cap, and means to feed the liquid upon the spreader.
5. A distributor of the character described comprising a casing, a container for a liquid disinfectant or deodorizer mounted within the casing, said casing having outlet openings therein below the container and an inlet opening in its lower end below the outlet opening, a hollow spreader member interposed between the container and lower end of the casing, said member having openings therein communicating with the openings in the bottom of the container, means to feed the contents of the container upon the spreader member, and a nozzle projecting upwardly from the opening in the bottom of the container into the hollow spreader member.
6. A distributor of the character described comprising a casing, a container for a liquid disinfectant mounted within the casing and spaced from the lower end thereof, said casing having an air intake opening in the lower end thereof, a hollow deflector and spreader member comprising an angular irregular surface over which the liquid spreads mounted within the casing in the lower end thereof and communicating with the opening in the bottom of the casing, said member having openings therein to cause the interior thereof to communicate with the casing, said casing having outlet openings therein between said member and the container, and means to feed liquid from the container so that it will drop upon and spread out over the deflector and spreader member.
7. A distributor for disinfectants and deodorizers comprising a casing, a container for liquid disinfectants and deodorizers mounted within the casing, a conical deflector and spreader mounted within the casing below the container, and means to feed liquid from the container on to the deflector, said casing having openings in the sides thereof and provided with an air entrance opening at its upper end, said deflector having openings in the side thereof communicating with the air entrance opening.
8. A distributor for disinfectants and deodorizers comprising a casing, a container for liquid disinfectants and deodorizers mounted within the casing, a hollow substantially conical deflector and spreader mounted within the casing below the container, said casing having an air entrance opening therein communicating with the interior of the deflector, said deflector having openings in the side thereof communicating with the casing and air entrance opening, said casing having openings in the sides thereof above the deflector, said conical deflector including a series of annular substantially horizontal surfaces arranged one above the other, and means to feed liquid on to the deflector from the container.
9. A distributor for disinfectants and deodorizers comprising a casing, a container for liquid disinfectants and deodorizers mounted within the casing, a deflector and spreader member adapted to receive the disinfectant or deodorizer mounted within the casing beneath the container, said casing having openings in the sides thereof, said deflector and spreader member being of irregular outline and having its central portion of conical formation, and means to cause liquid from the container to drop upon the apex of the conical portion of the deflector and spreader member.
10. A distributor for liquid disinfectants and deodorizers comprising a casing, a container for liquid disinfectants and deodorizers mounted in the casing, a deflector and spreader member mounted within the casing beneath the container, said deflector and spreader member being hollow and of substantially conical outline with its convex face uppermost, means to direct liquid from the container on to the apex of the deflector and spreader member, said casing having an opening in its bottom wall communicating with the interior of the hollow deflector and spreader member, said spreader member having perforations in its side wall, and being of irregular contour, and said casing having a series of perforations therein.
11. A disinfectant distributor comprising a casing, a liquid disinfectant container mounted within the casing, a cap removably secured to and closing the lower end of the casing, said cap having an air entrance opening therein, said casing being provided with a series of air outlet openings therein, a hollow conical deflector and spreader member mounted within the casing with its convex face uppermost and supported by the cap, said deflector and spreader member having a plurality of annular offset portions and provided with perforations therein, the portion of said deflector member in which the openings are formed being substantially upright, and means to direct liquid from the container onto the apex of the deflector and spreader member.
12. A disinfectant distributor comprising a casing, a liquid disinfectant container mounted within the casing, a cap removably

secured to and closing the lower end of the casing, said cap having an air entrance opening therein, said casing being provided with a series of air outlet openings therein, a hollow conical deflector and spreader member mounted within the casing with its convex face uppermost and supported by the cap, said deflector and spreader member having a plurality of annular offset portions and provided with perforations therein, the portion of said deflector member in which the openings are formed being substantially upright, means to direct liquid from the container onto the apex of the deflector and spreader member, and a nozzle in the opening in said cap extending up into the hollow deflector and spreader member.

13. A disinfectant distributor comprising a casing, a liquid disinfectant container mounted within the casing, a cap removably secured to and closing the lower end of the casing, said cap having an air entrance opening therein, said casing being provided with

a series of air outlet openings therein, a hollow conical deflector and spreader member mounted within the casing with its convex face uppermost and supported by the cap, said deflector and spreader member having a plurality of annular offset portions and provided with perforations therein, the portion of said deflector member in which the openings are formed being substantially upright, means to direct liquid from the container onto the apex of the deflector and spreader member, and a nozzle in the opening in said cap extending up into the hollow deflector and spreader member, the lower edge of the hollow deflector and spreader member being cut away at spaced points.

Signed at Los Angeles, California, this 2d day of December, 1915.

HARRY TOPLITZKY.
